COMPRESSOR WITH COMPRESSED AIR REACTIVE DRIVE

Alfred M. Caddell, 1318 W. Hunting Park Ave., Philadelphia 40, Pa.

Original application Apr. 11, 1956, Ser. No. 577,567.
Divided and this application June 5, 1957, Ser. No. 663,765

4 Claims. (Cl. 230—127)

This application is a division taken from pending application entitled Centrifugal Fluid Compressor With Axial Delivery, filed April 11, 1956, Serial No. 577,567.

Fig. 1 is a composite, frontal view of a rotor assembly taken on the lines 1—1, Fig. 2.

Fig. 2 is a cross-sectional view of the rotor shown in Fig. 1.

Fig. 3 is a view, taken on the lines 3—3, Fig. 1, showing in cross section the concavo-concave vane structures employed in the rotor and the air-flow relation of each vane structure to the other.

Fig. 4 is an enlarged side view of a single vane structure, such as those shown frontally in Fig. 1. This view shows the canopy of the disc's rim section spanning the attack side of the vanes.

Fig. 5 is an enlarged exposed top view of a section of the disc taken on the lines 5—5, Fig. 2, showing the chambered head in the rim of the disc and nozzles protruding from a flange secured to said head.

Fig. 6 is a composite rear view of the compressor, taken on the lines 6—6, Fig. 2.

Fig. 7 is a three-quarter partial view of the ring of stator formations, taken on the lines 7—7, Fig. 1.

Fig. 8 is a side view of the stator receiving and deflecting blade formations, identified as 22, Figs. 1, 2, 7, 8 and 9.

Fig. 9 is a three-quarter view of a single stator blade showing the cup-like formation and flow-deflecting sections thereof.

The principal differences between the rotor described in Serial No. 577,567 and that described herein lies in the configuration of the vanes and the chambered rim section of the disc that carries the vanes. The trailing half of the vane structures illustrated in the pending case and those shown in this application deflect air into the vane following next in rotation. But instead of hoods capping the attack side of the vanes, as in the pending application, the presently described disc has a rim structure that carries a plurality of chambers which receive the radially pumped air from the vanes. Whereupon the air, as well as being compressed in the chamber, is turned at a right angle relative to the vanes and discharged obliquely therefrom in a direction opposite to that of rotation. This discharge occurs at the maximum leverage position in the disc, thereby contributing greatly to reactive drive effect.

To trace the flow of air through this compressor: Air enters the confines of casing 1, as indicated by a plurality of arrows 2, Fig. 2, and strikes against concavo-concave vane structures 3 of rotor 4. The construction and interrelation of these vane structures may be observed by referring to the cross sectional view in Fig. 3. The numeral 3A identifies the attack or pumping side of the vanes; 3B the deflecting side and 3C the base part of the structures, which base seats in a recess in disc 4, being secured thereto by a plurality of screw bolts 5. The relation between the deflecting and the pumping side of the

2

vanes is shown in Fig. 3, arrows 6 indicating how the air deflects from 3B into 3A of the vane following next in rotation.

Upon being rotated, the attack side of the vanes becomes a powerful centrifugal pump, throwing air into chambers 7 in rim section 4A of the disc. These chambers, which are formed at a right angle relative to the vane structures, have comparatively large receiving areas which span pumping vanes 3A at their radial ends. 10 Whereupon said chambers become progressively reduced in cross section as they obliquely traverse the rim section of the disc. This disc carries annular plate 20 which, in turn, carries a plurality of nozzles 21 through which the compressed air is discharged in a direction opposite to that of rotation. By reducing the cross sectional area of the chambers, compression pressure in the air is transformed into velocity pressure prior to its discharge from the nozzles, thereby increasing reactive drive effect. Arrows 28, Fig. 6, indicate the opposite-to-rotation directional discharge of the gas, while arrow 29 shows direction of rotation of the disc.

Casing 1 is of divided construction, each half thereof being secured to the other by bolts 27 at flanges 1A of each half.

25 As shown in Figs. 2, 4 and 5, disc 4 has a divided construction mainly for accurately forming chambers 7 which extend through rim section 4A. Each half has spline notches 4B on their inner sides for mating and stress-supporting purposes, after which said walls are secured to each other by a plurality of screw bolts 5, shown in dotted outline in Figs. 2 and 4.

Vane structures 3 protrude forwardly in their central areas to increase their air-attacking and air-deflecting capacity and to minimize shock of the air attack, after 35 which said structures blend radially to parallel the walls of the disc. Short arrows 8 indicate the ultimate radial flow of the pumped air into receiving chambers 7 which span the tops of the vanes' attacking sides. Vane structures 3 may be secured to rim 4A by welding means, 40 as at 9, Fig. 4.

The deflecting sides 3B of these structures overcome to a great extent the vacuous drag that would otherwise trail in the wake of the vanes as they move through the air. Also, upon the compressor moving forward through air, 45 the encountered air pressure impinges forcibly upon the 3B surfaces; which pressure translates instantly into powerful reactive drive. If this compressor is mounted in an aircraft, upon the craft attaining a forward speed of 375 miles per hour, the ram pressure imparted by the encountered air is so great that little or no power from an engine is required to supply the needed poundage of air for combustion and air dilution purposes; which suggests that with an increasing ram pressure effect made 50 possible by deflecting sides 3B, the maximum air requirements for a gas turbine engine, independent of the power supplied by the engine, may be had at a forward speed much lower than that of 375 miles per hour.

Disc 4 is mounted on shaft 10, which is positioned between bearing assemblies 11 at the shaft's forward 55 end and 12 at its rear, the inner race of said assemblies being secured in position on the shaft by keys 25 and 26 respectively and locked in position by locknuts 13 and 14. The bearing assemblies are, in turn, mounted in the hubs of the forward and rear open framework spider assemblies 15 and 16 which are secured at their radial extremities to casing 1 by suitable means.

Plate 17, which is positioned between open framework assembly 15 and within close proximity to disc 4, is mounted annularly around and secured to the inner wall 70 of casing 1 by screw bolts 18, and to framework 15 by screw bolts 19. In addition to lending strength to the com-

pressor assembly, plate 17 deflects air into the vanes for reactive drive and pumping purposes.

Annular plate 20 is secured in a recess in the discharge side of disc 4, as shown in Figs. 2 and 5. This plate holds a plurality of nozzles 21, the entrance ends of which abut chamber orifices 7A, thus permitting a continuous flow of air therethrough. By means of this plate insert, nozzles having different performance characteristics may be installed for determining the most efficient design.

Upon being discharged from nozzles 21, the compressed air strikes a ring of stator formations 22, shown in Fig. 2 and as separate views in Figs. 7, 8 and 9. While reactive drive brought into being by virtue of the compressed air being discharged in a direction opposite to that of rotation is just as powerful without a stator formation being employed, the formation herein described turns the air in an axial direction immediately upon its impingement thereagainst.

It will be noted by viewing Figs. 8 and 9, the compressed air strikes a cup-like curvature in the forward part of the stator formation and deflects it as per arrows 23, Fig. 8, against the reverse or underside of a preceding formation, causing the air to undergo rapid transformation from an opposite-to-rotation direction to an axial direction. As shown in Figs. 2 and 6, after being deflected into the desired direction by said stator formations, the air enters ducts 24 to be conveyed thereby to any desired destination.

By means of this invention it is felt that the large frontal area handicaps associated with present-day centrifugal compressors may be overcome; also that the added efficiency made possible by preventing the formation of power-consuming vacuum drag, harnessing ram pressure of air to assist in the compressor's rotation, obtaining reactive drive in the vane part of the structures by powerful deflection of air, and obtaining reactive drive by discharging the compressed air through diverging nozzles in a direction opposite to that of rotation, will greatly minimize the power required to obtain the needed poundage of air for efficient gas turbine use.

Having described my invention, I claim:

1. In a centrifugal fluid compressor, an outer casing open at its forward end to form an intake duct for air, a rotor rotatably supported in said casing for compressing air radially and discharging it in a direction opposite to that of rotation, a ring of stator blades mounted in close proximity to said rotor and in communication with the discharge of said air therefrom for deflecting said air axially within said compressor, said rotor being comprised of a disc and a plurality of concavo-concave structures, said disc having a rear wall, a forward wall and a rim section extending forwardly therefrom to form a canopy, a plurality of recesses formed in the forward wall, said concavo-concave structures having base sections mounted in said recesses, said structures projecting forwardly from said bases into free air, one side thereof having a concave blade for pumping air radially as it advances in the direction of rotation and the other side having a curved formation for deflecting air from the back of said pumping blade into the pumping blade following next in rotation, each of said structures terminating short of said canopy and being made secure thereto, chambers formed in said canopy for receiving air pumped by said blades, said chambers continuing diagonally through said rim section to the rear wall of said disc to form a channel having a lesser gross sectional dimension at its terminus than that portion of the chamber immediately radial to said pumping blade, an annular recess formed in the rear wall of said disc inwardly of its periphery, a plate formed to fit said recess, a set of nozzles having communication with said channels and extending through said plate, said nozzles having a diverging cross sectional construction

protruding outwardly from said plate, the wall of said nozzles being curved in a direction opposite to that of the rotation of said rotor, said nozzles communicating with said chamber and having outlet ends discharging in a direction opposite to that of the rotation of the rotor.

5 2. In a disc as described in claim 1, a plurality of chambers formed in the rim section thereof, the walls comprising said chambers having a rounded contour immediately radial to the peripheral end of said blades for receiving air centrifuged thereagainst and deflecting it therewithin and into said nozzles to be discharged therefrom in a direction opposite to that of rotation of said rotor.

10 3. In a centrifugal fluid compressor for compressing air radially and discharging it axially from within its confines at substantially the maximum radius thereof, an outer casing open to atmosphere and adapted to move forward therethrough, a disc mounted for rotation in said casing, said disc having a rear wall, a forward wall and a rim section extending forwardly therefrom to form a canopy, a plurality of recesses formed in said forward wall, an equivalent number of concavo-concave structures having bases fitting said recesses and projecting forwardly therefrom into free air, said structures having a side advancing in the direction of rotation and a side trailing relative to the direction of rotation of said disc, said advancing side having a curvature for pumping air radially and said trailing side a curvature for deflecting ram pressure air encountered in the forward movement of said casing into the pumping side of the structure advancing next in rotation, an equivalent number of chambers formed in said canopy immediately radial to said pumping side and communicating therewith, said chamber walls diagonally traversing said rim section and having progressively decreasing cross sectional areas extending toward said rear wall, a plurality of nozzles of diverging cross section mounted in said rear wall and having communication with said areas, a stator blade formation having a plurality of blades mounted on the inner wall of said casing, encompassing and communicating with said nozzles and being positioned in close proximity to said disc, said nozzles projecting outwardly from the rear wall of said disc and curving to parallel the outer side thereof and discharging said air in a direction opposite to that of rotation against the blades of said stator formation.

15 4. In a centrifugal compressor as described in claim 3, said stator blades having a semi-cup formation for receiving thereagainst in a direction opposite to that of the disc's rotation the discharge of air from said nozzles, said blades thereafter having a curving configuration that blends with said semi-cup formation and extends rearwardly to parallel the axis of said disc, the surface of the configuration of one blade comprising in conjunction with the opposite surface of the configuration of a neighbor blade a channel for directing axially the air striking said semi-cup formation.
